UNITED STATES PATENT OFFICE.

JOSEPH P. MINGLE, OF MUNCIE, INDIANA, ASSIGNOR TO BALL BROTHERS GLASS MANUFACTURING COMPANY, OF MUNCIE, INDIANA, A CORPORATION OF INDIANA.

LEER FEEDER.

Application filed March 23, 1922. Serial No. 546,021.

To all whom it may concern:

Be it known that I, JOSEPH P. MINGLE, a citizen of the United States, residing at Muncie, in the county of Delaware and 5 State of Indiana, have invented a new and useful Leer Feeder, of which the following is a specification.

My invention relates to improvements in charging or loading devices for leers, furnaces, and the like. One of the objects of 10 my invention is to provide a charging or loading apparatus particularly designed for handling glass ware and the like which shall smoothly and easily introduce the articles into the leer with the maximum speed 15 and minimum breakage.

Another object of my invention is to provide a charging means which will introduce the articles into the leer, furnace, or the 20 like without stopping the movement of the articles on the conveyor which carries the articles across the charging opening of the leer.

For the purpose of disclosing my invention I have illustrated one embodiment 25 thereof in the accompanying drawings, in which:

Fig. 1 is a front elevation of a leer showing my improved charging device in position;

Fig. 2 is a side elevation thereof;

Fig. 3 is a sectional view taken on the line 3-3 of Fig. 2; and

Fig. 4 is a detail section taken on the 35 line 4-4 of Fig. 3.

In the embodiment illustrated, traveling immediately in front of the leer 5 and adjacent the receiving opening thereof is a continuously moving article conveyor 6 which at one end is adapted to pass over 40 a suitable sprocket 7. This conveyor is of the usual type and the glass or other articles intended to be fed into the leer are placed thereon and are fed by the conveyor across 45 the front entrance of the leer.

For the purpose of moving the articles off the conveyor and introducing them into the leer I provide a pusher bar 8 which is adapted to move transversely across the conveyor and at the same time move in the direction of travel of the conveyor. This pusher bar at the end from which the articles approach has a rearwardly extending finger 9 to prevent, in event of an accidental 50 stopping of the pusher bar in its movement 55

across the conveyor, the articles from being conveyed behind the bar and being pulled off the conveyor during the retractile movement thereof.

The pusher bar is supported by a pair 60 of horizontally disposed arms 10 secured at the lower end of a pair of vertical bars 11 which in turn, at their upper ends, are supported upon and secured to the forward end of a rectangular frame 12, the pusher bar 65 being additionally braced by means of brace bars 13 which extend from the rear end of the frame 12 to the arms 10. The rectangular frame 12 is supported at four points by and operates in a plurality of guideways 14, 70 each comprising a pair of horizontally disposed spaced-apart bars or rods, which guideways are in turn secured upon a channel member 15 hung by means of rods 17 from suitable supporting beams 16 project- 75 ing from the face of the leer.

The guideways 14 extend parallel with the line of travel of the conveyor and the two side members 18 of the frame 12 operate therein. These guideways permit a 80 transverse movement of the frame 12 relative to the line of travel of the conveyor and also a movement of the frame in a direction coincident to the line of travel of 85 the conveyor.

Mounted on the underside of the channel 15 are a pair of cam members 19 and 20. These two cam members are of the same construction so that a description of one will be sufficient. On the under face of the cam member 19 there is provided a cam groove having a triangular path. The base 21 of the triangle is parallel to the line of movement of the conveyor 6 past the front of the leer while the two legs 22 and 23 of the triangle extend toward the leer. A suitable roller 24 secured upon one of the side members 18 of the frame 12 operates in the cam track of the member 19 and a similar roller 25 secured to the opposite side 90 member operates in the cam track of the cam member 20.

To insure the travel of the rollers in the right direction, shown by the arrows in Fig. 3, at the junction of the leg 23 with the base 105 21 there is provided a gate 26 on a pivoted arm 27 provided on its underside with a cam face 28. As the roller passes beneath the cam the gate is raised but when the roller enters the track of the base 21 the 110

gate closes to prevent the roller from again entering the track of the leg 23. A similar gate 29 is provided where the track of the base 21 joins the track of the leg 22.

5 The pin on which the roller 25 is mounted extends downwardly to engage in a socket formed in the end of a piston rod 30 reciprocated by a piston 31 operating in a cylinder 32. This cylinder is pivotally mounted on the under side of the channel 15 and at each end is provided with inlet and discharge openings connected respectively with inlet and discharge pipes 33 and 34. The inlet and discharge pipes 33 and 34 at one end of the cylinder are connected to a pipe 35 and at the opposite end to a pipe 36. These pipes 35 and 36 are connected to a valve member 37 connected with a fluid pressure supply pipe 38 and having an exhaust opening 39. This valve member is operated by a cam 40 driven by a gear 41 meshing with a gear 42 mounted upon the shaft of the sprocket 7 and the operation of the valve is timed to reverse the pressure in the cylinder at the moment the frame 12 reaches the end of its longitudinal movement in either direction. Each of the inlet pipes 33 is provided with a check valve 43 and each of the discharge pipes 34 40 is provided with a globe valve 44 by which the rate of escape of the fluid under pressure from the cylinders may be graduated to synchronize the speed of the forward longitudinal movement of the pusher bar with that of the conveyor. The retractile longitudinal movement of the bar may of course be any speed desired.

40 The piston 31 near the limit of its movement in each direction covers the escape opening leading to discharge pipe 34 so that an air cushion will be formed between the piston and end of the cylinder to cushion the movement of the cylinder and the parts operated thereby.

45 Longitudinal reciprocatory movement is imparted by means of the piston 31 to the pusher bar 8 and due to the shape of the cam track in the cam members 19 and 20 a transverse reciprocatory movement is imparted to the pusher bar 8 while it is traveling forward with and at the same speed as the conveyor.

50 In operation, when pressure is admitted to the cylinder 32 and at the left of the piston 31 movement is imparted to the frame 12 and pusher bar 8 to cause the frame to travel with and in the direction of movement of the conveyor. The rollers 24 and 25 operating in the leg 22 of the cam track will at 55 the same time impart a movement to the pusher bar 8 across the conveyor so that the pusher bar 8 will engage the articles and push them off the conveyor and into the leer. During this transverse movement however 60 the pusher bar will be traveling forward at

approximately the same rate of speed as the conveyor. When the rollers reach the apex of the triangular track the forward transverse movement of the pusher bar will be completed and the bar will have been moved 70 a distance slightly greater than the width of the conveyor. The rollers now entering the leg 23 of the track, the bar 8 will be retracted across the conveyor continuing however to move with the conveyor so that it will 75 not interfere with the articles on the conveyor or cause them to pile up. When the bar 8 reaches the limit of its forward longitudinal movement pressure on the piston is reversed and, with the rollers operating in 80 the base track 21, the bar 8 will be retracted to its original position with a right-line movement.

I claim as my invention:

1. In a leer feeding mechanism, the combination with a continuously moving article carrying conveyor traveling in front of the leer mouth, of a pusher for moving the articles carried thereon transversely to and off said conveyor, said pusher having a simultaneous movement transversely to the line of travel of the conveyor and in a direction with the line of travel of the conveyor. 85

2. In a leer feeding device, the combination with a continuously moving article carrying conveyor traveling in front of the leer mouth, of a pusher for moving the articles carried thereon transversely to and off the conveyor and means for operating the pusher to move the same across the conveyor while 90 traveling with the conveyor. 95

3. In a leer feeding device, the combination with a continuously moving article carrying conveyor traveling in front of the leer mouth, of a pusher for moving the articles 105 carried thereon transversely to and off the conveyor having reciprocatory movement longitudinal to the line of travel of the conveyor, and a reciprocatory movement transversely to the line of travel of the conveyor. 110

4. In a leer feeding device, the combination with a continuously moving article carrying conveyor traveling in front of the leer mouth, of a pusher for moving the articles 115 carried thereon transversely to and off the conveyor having a reciprocatory movement longitudinally of the line of travel of the conveyor, and a reciprocatory movement transversely of the line of travel of the conveyor during a portion of said first mentioned reciprocatory movement. 120

5. In a feeding device, the combination with a continuously moving article carrying conveyor, of a pusher for moving the articles carried thereon off the conveyor traveling in a triangular path, the apex of the triangular path projecting toward the conveyor and the base of the triangle being parallel 125 with the line of movement of the conveyor. 130

6. In a leer feeding device, the combination with a continuously moving article carrying conveyor traveling in front of the leer mouth, of a pusher for moving the articles carried thereon transversely to and off the conveyor moving with and at approximately the same speed as the conveyor and having during said movement a reciprocatory movement transversely of the conveyor.
- 10 7. In a feeding device, the combination with a continuously moving article carrying conveyor, of a pusher for moving the articles carried thereon off the conveyor moving with and transversely of the conveyor and having a retractile movement parallel with the conveyor.
- 15 8. In a leer feeding device, the combination with a continuously moving article carrying conveyor traveling in front of the leer mouth, of a pusher for moving the articles carried thereon transversely to and off the conveyor extending parallel with the line of movement to said conveyor, means for imparting a simultaneous movement to said pusher in the direction of the line of movement of the conveyor and transversely thereto while maintaining said pusher parallel with the line of movement of the conveyor.
- 20 9. In a feeding device, the combination with a continuously moving conveyor, of a pusher, a pair of stationarily mounted triangular cams having their bases parallel with the line of movement of the conveyor and their apexes extending toward the conveyor, rollers connected to said pusher and arranged to engage said cams, and means for imparting a reciprocatory movement to the pusher in the direction of the line of travel of the conveyor.
- 25 10. In a feeding device, the combination with a continuously moving conveyor, of a pusher, a triangular cam member having its
- base parallel with the line of movement of the conveyor and its apex extending toward the conveyor, a cam engaging member, one 45 of said members being stationarily mounted and the other connected with said pusher and means for imparting to said pusher a reciprocatory movement in the direction of the line of travel of the conveyor.
- 50 11. In a feeding device, the combination with a continuously moving conveyor, of a pusher, a fluid-pressure operated piston for imparting to said pusher a reciprocatory movement in the direction of the line of 55 travel of the conveyor, means for cushioning said piston at the limit of its stroke, and means for imparting to said pusher a movement transverse to the line of travel of the conveyor while it is moving in the same direction as the conveyor.
12. In a feeding device, the combination with a continuously moving conveyor, of a pusher, a pair of triangular cam members having their bases parallel with the line of 60 movement of the conveyor and their apexes extending toward the conveyor, a pair of cam engaging members secured at the opposite ends of said pusher arranged to engage said cams, and means for imparting a reciprocatory movement to the pusher in the direction of the line of travel of the conveyor.
13. In a feeding device, the combination with a continuously moving conveyor, of a pusher, and means including a cam for producing a lateral and longitudinal movement of the pusher in the direction of travel of the conveyor, and a retractile movement of the pusher free from the conveyor.
- 75 In witness whereof I, JOSEPH P. MINGLE, 80 have hereunto set my hand at Muncie, Indiana, this 18th day of March, A. D. one thousand nine hundred and twenty two.
- JOSEPH P. MINGLE.
